PORTABLE BAR

Frank B. Thompson, 719 Tammy Drive,
San Antonio, Tex. 78216

Filed June 11, 1973, Ser. No. 368,971

Term of patent 14 years

Int. Cl. D12—02; D6—06
U.S. Cl. D12—22

FIG. 1 is a left front perspective view of a portable bar showing my new design.

FIG. 2 is a left rear perspective view thereof with the bulk storage drawer open, it being understood that the opposite side of the panel in the bulk storage drawer is substantially plain and unornamented.

The undisclosed side is substantially a mirror image of the side shown.

I claim:

The ornamental design for a portable bar, as shown and described.
